TRIPOD LEG CLAMP

Joseph Stiles Beggs, Rochester, N. Y., assignor to
 Eastman Kodak Company, Rochester, N. Y., a
 corporation of New Jersey

Application May 22, 1937, Serial No. 144,230

10 Claims. (Cl. 248—191)

This invention relates to tripods of the type generally used for supporting cameras, surveying instruments, and the like, which are provided with a plurality of extensible supporting legs which comprise slidably united sections; and particularly to the means for rigidly clamping these slidably united sections in any desired position.

Ordinary tripods, such as are at present commonly used in cameras of various kinds, surveying instruments, etc., are constructed with light adjustable and collapsible legs. To provide light, strong, and rigid devices the legs are each formed of two upwardly diverging sides, and in order that they may be adjustable and collapsible the legs are constructed in sections adapted to adjustably telescope. The clamping means generally provided with this type of leg structure for holding the telescoping leg sections in adjusted position are inconvenient to operate so that a considerable amount of time is required for properly setting up the tripod. In addition, most tripods having adjustable leg sections as above described are designed primarily for supporting objects which are comparatively light, and as a result the clamping means for the legs are not designed to give a clamping action which will support the heavier cameras as used by professionals.

Therefore, one object of the present invention is the provision of a clamping means for the telescoping legs of a tripod which is easy to manipulate without inconvenience to the operator. Another object is the provision of a clamping means the operating handle of which can be used to adjust the telescoping leg sections into the desired position so that only one hand is required to adjust and clamp any one leg section. A further object is the provision of a clamp by means of which the adjustable leg can be frictionally secured in any desired position rigidly enough to support a comparatively heavy weight. And still another object is the provision of a clamping means which is so designed that only a comparatively slight adjustment of the operating handle is required to alter the clamping means from a locking to an unlocking position. Another object is to provide a clamping means the engaging parts of which are enclosed so that they are protected against the elements and the accumulation of dirt. And yet another object is to provide a clamping means which is neat in appearance, designed for long life, and constructed so that the parts thereof cannot become disengaged and lost.

The novel features that I consider characteristic of my invention are set forth with particu-

larity in the appended claims. The invention itself, however, both as to its organization and its method of operation, together with additional objects and advantages thereof, will best be understood from the following description of specific embodiments when read in connection with the accompanying drawing in which,

Fig. 1 is a side elevation of a tripod, and showing the preferred embodiment of my invention applied thereto, 10

Fig. 2 is an enlarged sectional view taken substantially on line 2—2 of Fig. 1, and showing one embodiment of the clamping structure.

Fig. 3 is a horizontal section taken through one of the clamps, and showing the preferred embodiment of my structure in unlocking position, 15

Fig. 4 is a similar to Fig. 3 but shows the clamp in locking position, and

Fig. 5 is a section taken on line 5—5 of Fig. 1.

Like reference characters refer to corresponding parts throughout the drawing.

Referring now to the drawing, numeral 10 designates a tripod head which is supported by legs 11. Each tripod leg 11 comprises angular leg sections 12 to the upper ends of which are bolted brackets 13. These brackets 13 engage extensions 14 on the tripod head and are pivotally connected thereto by a clamping bolt 15 by means of which the legs 11 can be held in any desired angular position relative to the tripod head. 30 Angular leg sections 16 are connected at their lower ends by a coupling 17 and diverge upwardly in telescoping relation with respect to the angular leg sections 12, as shown clearly in Figs. 2—5. Bands 18 are fixed to the lower leg sections 12 by 35 screws 19 to extend around and form a guide for the leg sections 16 which telescope with the leg sections 12, see Fig. 5. Supporting feet indicated at 9 can be removably attached to the coupling 17 in any suitable manner, said feet having 40 pointed or rubber ends as may be desired.

The upper ends of the leg sections 16 are fastened to rectangular casings 20 which serve both as a housing in which the clamping mechanism is enclosed and as a guide member for holding the two angular leg sections 12 and 16 in telescoping relation, as will be hereinafter described. Each casing 20 constitutes a substantially closed housing, the top 21 and bottom 21' of which are provided with angular openings 22 through which 45 the leg sections 12 and 16 extend to be held in telescopic relation. The upper ends of the angular sections 16 extend completely through the bottom of the casing and through the top of the casing far enough to be flush with the outer sur- 50 55

face of the top 21 thereof, see Figs. 1 and 2. The angular leg section 16 is situated in one corner of the casing 20 so that its arms are fastened to the wall of the casing in any suitable manner such as by rivets 43 as shown in Figs. 2-4. The angular section 12 extends completely through the angular opening 22 in the top and bottom of the casing 20 to be guided in telescopic relation with the angular section 16 thereby, see Figs. 2-4.

As shown in Figs 3 and 4, a triangular pressure block 23 is situated in each casing 20 so that one of its vertices lies in the vertex of the angular leg section 12, and the surfaces of the legs thereof engage the faces of the arms of the angular section. A wedge 24 is movably mounted in each casing 20 to move crossways thereof, and is provided with an angular face 25 which is adapted to engage the hypotenuse of the triangular pressure block when moved theretoward.

The wedge 24 is provided with a bore 26 the one end of which is threaded to be engaged by a threaded end on the nut member 27. The nut member 27 extends through and is rotatably mounted with respect to an aperture in the wall 28 of the casing 20, and is provided with a flange 29 which engages the wall of the casing to prevent its passage through the aperture therein. It will be readily understood that when the nut member 27 is rotated in one direction, the wedge 24 will be drawn toward the wall 28 in the casing whereupon the face 25 thereof will engage the hypotenuse of the triangular pressure block 23 and will press said block toward the vertex of the angular section 12 and force this leg section into frictional engagement with the angular section 16 to thereby clamp the leg in its adjusted position, see Fig. 4. A rotation of the nut member in the opposite direction will move the wedge 24 away from the triangular pressure block 23 and will allow the angular section 12 to move away from the angular section 16 so that the leg section 16 can slide relative thereto. It will be appreciated that only a very slight movement of the wedge 24 is required between its locking and unlocking positions, and referring to Figs 3 and 4, it will be understood that the casing 20 is designed so as to permit sufficient movement of the wedge 24 for moving between its locking and unlocking positions, but not allowing sufficient movement thereof so that the nut member 27 and the wedge 24 can become disengaged.

Although the nut member 27 can be rotated in any manner to provide an adjustment of the wedge 24, in order that a simultaneous adjustment of the wedges 24 in their respective cases 20 of each leg 11 can be effected, I have provided the following structure. Each nut member 27 is provided with a hexagonal bore 30 into which the ends of a hexagonal adjusting rod 31 extends so that the rod is slidable axially to the nut member but cannot be rotated relative thereto. It is to be understood that the bore 30 in the nut member 27 and the adjusting rod 31 cooperating therewith can be of any complementary shape such as triangular, rectangular, or the like, so long as a splined fitting is provided. A handle 32 is situated on the adjusting rod intermediate the upper ends of the angular leg section 16, and 70 has a hexagonal bore engaging the hexagonal rod so that it can slide relative to the rod but cannot rotate with respect thereto, see Figs. 1 and 2. Coil springs 33 encircle the rod 31 on either side of a handle 32, and have one end engaging the nut member 27 and the other end

seated in a recess 34 in the end of the handle 32 which is coaxial with the hexagonal bore therein. These springs 33 tend to position the handle 32 on the rod 31 so that it will be equally spaced from each of the diverging leg sections 16 regardless of whether the leg is collapsed or fully extended.

So that the rotation of the adjusting rod 31 will effect a simultaneous clamping or unclamping action in each of the clamping mechanisms of any one leg 11, the threads on the nut members 27 are formed oppositely. In other words, the screw thread on one of the nut members 27 is left handed while the screw thread on the other nut member is right handed. It was discovered that when the adjusting rod 31 is rotated, the right and left hand nut members did not pick up their respective wedge members simultaneously, but one lagged slightly behind the other with the result that an uneven clamping occurred in the two clamps. To overcome this fact, equalizing spring washers 35 are positioned between the flange 29 on each of the nut members 27 and the wall 28 of the casing 20, see Figs. 3 and 4, and said spring washers serve to equalize the pressure on the two clamps by allowing the nut member 27 to move relative to the wedge 24.

The above described clamping means operates in the following manner: When the tripod leg 11 is to be adjusted the handle 32 is rotated in the proper direction to cause the wedges 24 to move into the unclamping position shown in Fig. 3. Without removing the hand from the handle 32, the angular leg sections 16 and the clamping means fixed thereto and enclosed in the casing 20, are pulled up or shoved downward as the case may be by pulling or shoving on the handle 32, and when the desired position is obtained the handle is rotated in the opposite direction to effect a clamping of the leg section. It will be appreciated that since this leg structure provides a clamping means whereby the operating handle can be used to extend the legs as well as clamp them in any adjusted position, one hand will suffice to adjust and clamp the leg while the other may be used to steady the instrument mounted on the tripod head.

From the above description it will be understood that as the angular leg sections 16 are extended from their collapsed position, shown in Fig. 1, the casings 20 will be moved toward one another due to the divergence of the leg sections. As the casings 20 move toward or away from one another during the adjustment of the legs 11, the adjusting rod 31 slides relative to the hexagonal bore in the nut members 27 and passes through the bore 26 in the wedge 24 and into the casing 20. The arrangement of the parts is such that when the legs 11 are collapsed and the angular leg sections 16 are spaced apart the maximum distance, the ends of the adjusting rod 31 will not pull out of the bore in the nut member 27; and when the legs are completely extended and the casings 20 are a minimum distance apart, the casing 20 will be deep enough to allow the ends of the rod 31 to pass thereinto.

Referring now to Fig. 2 wherein a second embodiment of my invention is shown, the entire structure is the same with the exception that the triangular pressure block 23 is replaced by a cylindrical roller 36 which lies in the vertex of the angular leg section 12. The roller 36 is situated in the casing 20 so that the elements of the periphery contact the surface of the arm of the angular leg section 12. The wedge 24

is modified slightly in shape as compared to the wedge 24 of Figs. 3 and 4 so that its face 25' will engage an element on the periphery of the roller 36 whereby a movement of the wedge toward 5 the wall 28 of the casing 29 will force the roller toward the vertex of the angular leg section 12 to force said leg section 12 into frictional clamping engagement with the angular section 16. It is obvious that the roller 36 which engages the 10 arm of the angular leg section 12 in line contact is not as effective in forcing said leg section into frictional engagement with the angular leg section 16 as is the triangular pressure block 23 which engages the arms of the leg section 12 15 through surface contact, but this embodiment is shown and described in order to illustrate one of the many ways in which my novel structure can be modified without going beyond the scope of the invention.

20 It will be readily understood that a clamping means for telescoping leg sections as above set forth is easy to manipulate and provides a very rigid joint with a slight movement of the adjusting means. By transmitting pressure from the 25 screw driven wedge 24 to the angular leg sections 12 through the medium of a triangular pressure block 23, which has a comparatively large area in surface contact with the arm of said angular leg section, a comparatively large 30 area of frictional contact is provided between the telescoping leg sections whereby a rigid clamping is secured. The particular arrangement of parts allows the clamping means to be released or locked through a slight adjustment 35 of the adjusting handle so that a rapid adjustment can be made without necessitating the release of said adjusting handle.

Although I have shown and described certain specific embodiments of my invention, I am 40 fully aware that many modifications thereof are possible. My invention, therefore, is not to be restricted except in so far as is necessitated by the prior art and by the spirit of the appended claims.

45 Having thus described my invention, what I declare is new and desire to secure by Letters Patent of the United States is:

1. In a tripod having an adjustable leg formed of adjustable telescoping sections, means for 50 frictionally clamping the sections together, said means comprising a casing surrounding said sections and fixed to one thereof, a pressure member in said casing and adapted to engage one of said sections, a wedge movably mounted in said casing and for applying pressure to said pressure member in a direction to force the telescoping section into frictional engagement with one another, and an adjusting means connected with 55 said wedge for moving it into and out of engagement with the pressure member.

2. In a tripod having an adjustable leg formed of telescoping angular sections, means for frictionally clamping the sections together, said means comprising a casing surrounding said sections and fixed to one thereof, a pressure member in said casing and adapted to lie in the vertex of one of said angular sections, a wedge movably mounted in the casing and adapted to engage and force said pressure member toward the 60 vertices of the angular sections to clamp the sections, and an adjusting means connected to the wedge for moving the same relative to the pressure member.

3. In a tripod having an adjustable leg formed 65 of telescoping angular sections, means for fric-

tionally clamping the sections together, said means comprising a casing surrounding said sections and fixed to one thereof, a cylindrical roller within said casing and situated in the angle of one of the angular sections so that its periphery 5 contacts the two surfaces constituting said angular section, a wedge movably mounted in said casing to engage and force the roller toward the vertex of the angular section to clamp the leg sections, and an adjusting means connected to 10 said wedge for moving the same relative to the roller.

4. In a tripod having an adjustable leg formed of telescoping angular sections, means for frictionally clamping the sections together, said 15 means comprising a casing surrounding said sections and fixed to one thereof, a triangular pressure block within said casing and situated in the vertex of one of the angular sections, a wedge movably mounted in said casing to engage 20 the hypotenuse of the triangular pressure block and force it toward the vertices of the angular sections to clamp the same, and an adjusting means connected to said wedge for moving the same relative to the pressure block. 25

5. In a tripod having an adjustable leg formed of telescoping angular sections, means for frictionally clamping the sections together, said means comprising a casing surrounding said sections and fixed to one thereof, a triangular 30 pressure block within said casing and situated in the vertex of one of the angular sections, a wedge movably mounted in said casing to engage the hypotenuse of the triangular pressure block 35 and force it toward the vertices of the angular sections to clamp the same, a nut extending through said casing into threaded engagement with said wedge, and means for rotating said nut to move the wedge into engagement with the pressure block to clamp said angular sections. 40

6. In a tripod having an adjustable leg formed of telescoping angular sections, means for frictionally clamping the sections together, said means comprising a casing surrounding said sections and fixed to one thereof, a triangular 45 pressure block within said casing and situated in the vertex of one of the angular sections, a wedge movably mounted in said casing to engage the hypotenuse of the triangular pressure block 50 and force it toward the vertices of the angular sections to clamp the same, a nut extending into and rotatably mounted with respect to said casing, said nut being in threaded engagement with the wedge and having a polygonal bore, and a polygonal rod slidably in said bore and for 55 rotating said nut to move said wedge into engagement with the pressure block whereby the angular sections are frictionally clamped.

7. In combination, a pair of telescoping angular sections, a casing surrounding said sections and fixed to one thereof, a second pair of telescoping, angular sections spaced from the first mentioned pair, a casing surrounding the second pair of sections and fixed to one thereof, a triangular pressure block within each casing and situated 65 in the vertex of one of the angular sections, a wedge movably mounted in each of said casings to engage the hypotenuse of the triangular pressure block therein and force it toward the vertex of the angular sections to clamp the same, an 70 adjusting means for each wedge member for moving the same into and out of engagement with its respective pair of angular sections, and a single operating member connecting both of said adjusting means whereby the separate 75

wedge members can be simultaneously moved into or out of clamping position in their respective casings through the actuation thereof.

8. In combination, a pair of telescoping angular sections, a casing surrounding said sections and fixed to one thereof, a second pair of telescoping angular sections spaced from the first mentioned pair, a casing surrounding the second pair of sections and fixed to one thereof, a triangular pressure block within each casing and situated in the vertex of one of the angular sections, a wedge movably mounted in each casing to engage the hypotenuse of the triangular pressure block therein and force it toward the vertices of the angular sections to clamp the same, a nut member extending through and rotatably mounted with respect to each of said casings, each of said nut members being in threaded engagement with the wedge in its associated casing and having a polygonal bore therethrough, and a polygonal rod having its ends extending into the bores in the nut members whereby a rotation of said rod will cause the nut members to rotate and move the wedge members into or out of their clamping positions simultaneously depending upon the direction of rotation of said rod.

9. In combination, a pair of telescoping angular sections, a casing surrounding said sections and fixed to one thereof, a second pair of telescoping angular sections spaced from the first mentioned pair, a casing surrounding the second pair of sections and fixed to one thereof, a triangular pressure block within each casing and situated in the vertex of one of the angular sections, a wedge movably mounted in each casing, to engage the hypotenuse of the triangular pressure block therein and force it toward the vertices of the angular sections to clamp the same, a nut member extending through and rotatably mounted with respect to each of said casings, each of said nut members being in threaded engagement

with the wedge in its associated casing and having a polygonal bore therethrough, a polygonal rod passing through the bores of the nut members to be slidable but not rotatable with respect thereto, a handle slidably mounted on but fixed against rotation with respect to said polygonal rod between the pairs of angular sections for rotating the same, and resilient means acting on said handle for normally holding it equally spaced intermediate the pairs of angular sections regardless of the relative position of the ends of the polygonal rod and the nut members.

10. In combination, a pair of telescoping angular sections, a casing surrounding said sections and fixed to one thereof, a second pair of telescoping angular sections spaced from the first mentioned pair, a casing surrounding the second pair of sections and fixed to one thereof, a triangular pressure block within each casing and situated in the vertex of one of the angular sections, a wedge movably mounted in each casing to engage the hypotenuse of the triangular pressure block therein and force it toward the vertices of the angular sections to clamp the same, a nut member extending through and rotatably mounted with respect to each of said casings each of said nut members being in threaded engagement with the wedge in its associated casing and having a polygonal bore therethrough, a polygonal rod passing through the bores of the nut members to be slidable but not rotatable with respect thereto, a handle slidably mounted on but fixed against rotation with respect to said polygonal rod between the pairs of angular sections for rotating the same, and means associated with each of the nut members and arranged to effect the relative axial movement between the nut member and its respective wedge, and for equalizing the pressure on the two clamps.

JOSEPH STILES BEGGS.
